Zebulon Hunt, of Hudson, A. Y.
Letters Patent No. 1347. Dated Mar. 4, 1860.

The schedule referred to in these ^{drawings} Letters Patent and making part of the same.
^{drawings}
To all whom it may concern:

Be it known that I, Zebulon Hunt, of the City of Hudson, in the County of Columbia and State of New York, have invented or produced a new and original design for the plates or castings of a Cooking Stove; and I do hereby declare that the following is a full and exact description of the same.

Fig. 1. of the annexed drawings is a front view or elevation of the stove, and
Fig. 2, is a side view of the same.

Fig. 3, 5 and 6, represent the mouldings employed for ornamenting the
Doors and Panels and

Fig. 4. is a transverse section of one of the doors, exhibiting the relative
position and style of the mouldings and also the swelling form of the door-plates or castings.

I term my Stove, "The Model Cook." The front (Fig. 1) is enclosed
by two doors A and B, folding together in the middle, and each having an ornamented
panel in the upper half and a slide draught in the lower half.

The words "The Model Cook," are cast in relief on the bar or cross
piece between the front doors and the ash-pan.

Des. 1347

An Eagle with uplifted wings is cast in bas relief in each upper half or panel of the front doors. In the projection above the doors in front is the slide damper b , for reducing the fire. The side (Fig. 2) is provided with two ornamented doors - one large and the other small, each opening into the oven, and an ornamented panel E , in the upper right hand corner.

For the style of ornamentation and configuration of the doors and panels see the annexed drawings.

A transverse section of the waved moulding, Fig. 3 used on the door is shown in Fig. 4, and also of the rope moulding, Fig. 6, which is set on an elevated square s . The branches in each corner of the Door C , and the ornamented designs in Door D and panel E , are all cast in relief. From the rope moulding the doors and panels round down to the plane of the door or Stove, plated.

Below the panel E , at a is the grate stem for racking or shaking the fire and for dumping the grate, which stem is surrounded by a socket and does not project beyond the general surface of the side plate. The cross ridge moulding, Fig. 5 is employed as a band moulding at the bottom just below the doors and around the projection in front, wherein is placed the damper b .

That I claim as my invention and desire to secure by Letters Patent of the United States, is:

The combination and arrangement of figures, forms and mouldings, herein specified and represented in the annexed drawings, forming the ornamental design of the plates and castings of a cooking Stove.
